CLAIM

The ornamental design for a camera for photograph vending machine, as shown and described.

DESCRIPTION

FIG. 1 is a front, top, and right side perspective view of a camera for photograph vending machine showing our new design;

FIG. 2 is a rear, top, and left side perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The broken lines shown in the figures depict portions of the camera for photograph vending machine in which the design is embodied and form no part of the claimed design.
